TYPEWRITING MACHINE

Jesse A. B. Smith, Stamford, Conn., assignor to
Underwood Elliott Fisher Company, New York,
N. Y., a corporation of Delaware

Application March 5, 1932, Serial No. 596,964

25 Claims. (Cl. 197—126)

This invention relates to typewriting machines, and particularly relates to devices whereby carbon-sheets are interleaved with manifold work-web plies, and to associate devices, whereby the 5 composite work-web is directed to the typewriter-platen for typing successive forms thereon, and whereby the interleaved carbons may be retracted to register with fresh forms.

This application discloses an improvement over 10 the pending application of David W. Rubidge, Serial No. 407,251, filed November 14, 1929 (now Patent No. 1,896,465 dated February 7, 1933).

In certain typewriters of this kind, individual carbon-sheets are held at one end in blades, and 15 together with said blades are inserted between the work-web plies, the blades being attached to a carbon-carriage, mounted for movement toward and from the platen. By means of this carriage and the attached blades, the interleaved 20 carbon-sheets can be retracted to register with a fresh work-web form every time the typing on one form is completed; it being understood that the carbon-carriage carrying the aforesaid blades and carbon-sheets will have advanced with the 25 work-web in line-feed movement toward the platen during said typing.

In certain other kinds of manifolding typewriters, continuous rolls of carbons are employed, instead of the comparatively short aforesaid carbon-sheets, the carbon-rolls being mounted in the carbon-carriage. The axes of the rolls are 30 spaced laterally from the edges of the work-web, so that the rolled portions clear said web. A suitable length is unwound from the carbon-roll, 35 is carried transversely across the web, and is then turned over a diagonal guide disposed in the path of the web. By such turning the carbon is directed along the web toward the platen, enough carbon being unwound to suffice for manifolding 40 without interfering with said diagonal guide.

Owing to the difference between the substantial width of the carbon-rolls and the much narrower width occupied by the aforesaid blades, a carriage for the rolls takes up more room in the direction of carriage movement than does a carriage for the blades. Heretofore it has been the practice to extend the guides upon which the carbon-carriage moves, and thereby accommodate the wider carbon-roll carriage without reducing 45 its range of movement. In other cases where a wide carbon-roll carriage was used in a machine having guides of a length designed for a narrower blade-carriage, the range within which such wide carriage could move was reduced, owing to the 50 heretofore used arrangement of the carriage rela-

tively to its guides. Such reduction of the carriage-movement range resulted in a corresponding limitation of the length of form which could be manifolded without shifting the carbons.

A feature of the present invention is an arrangement for a carbon-carriage for wide carbon-rolls whereby a typewriter having guides designed for a narrow blade-carriage may, without change, receive the wider carbon-roll carriage without reducing the effective range of carbon-carriage movement, that is to say, just as long a form may be manifolded with the wider carriage as was manifolded with the shorter carriage.

The importance of this feature resides not only 70 in the possibility which it affords of applying wide carbon-roll carriages to guides that were designed for the narrower carriages; but there is also the advantage resulting from the weight of the typewriter-platen-carriage being kept down, 75 it being understood that the guides for the carbon-carriage are directly connected to the typewriter-platen-carriage, and that any extension of such guides increases said weight. Furthermore such increase in length and weight is at a point 80 remote from the main typewriter-carriage-guides and escapement-mechanism, and in its skewing effect every time the carriage is arrested the increased weight puts additional strain on said bearings and mechanism and is to be strictly 85 avoided.

The carriage includes a narrow truck which, in the illustrated embodiment of the invention, may accommodate different carbon-carriers. In the wide carrier the necessary width to accommodate the carbon-rolls and guides is obtained by 90 extending said carrier so that when mounted upon said truck, it overhangs the rear of said truck. In this way the guide-rail length is minimized and the weight of the complete typewriter-carriage is kept down.

Another feature of improvement relates to the diagonal carbon-guides. Heretofore, a number of vertically-spaced rods, separate from the diagonal guides and extending transversely of the 100 carbon-sheets at portions between the rolls and the edge of the work-web, were used to separate and thereby prevent fouling of said sheets. Said rods were fixed in the carriage and were closely spaced in accordance with the usual close packing 105 of the composite work-web plies. The insertion of the leading edges of the carbons between said closely-spaced rods required care, and to this extent limited the expeditiousness with which a composite work-web could be prepared.

According to the present invention, these vertically-spaced rods are incorporated with the diagonal guides, and in effect form rock-shafts on which said guides are mounted for swinging the guides from working positions between the plies to positions remote from the web.

As set forth in the aforesaid Rubidge application, the interleaving of the carbons with a work-web ply is facilitated by having the diagonal guides swingable. According to the present invention, improved means render the guides not only swingable, but easily removable from the carriage entirely, and, conversely, easily replaceable in said carriage. To these ends, each diagonal guide may include one of the aforesaid rock-shafts which also serve to space a carbon-sheet vertically.

An angularly-shaped wire or member is used and includes two portions, one portion forming the diagonal guide and being secured to one end of the rock-shaft, and the other portion forming a strut supporting the other end of the diagonal portion and being secured to the rock-shaft at a point spaced from the point where the diagonal portion is secured to said shaft. There is thus formed a triangle having a rock-shaft, the diagonal portion and the strut-portion as its sides. The rock-shaft extends sufficiently beyond the triangle thus formed, so that it may be journaled in supports, each support including a series of vertically-spaced bearings, which, in conjunction with novel formations on the ends of a rock-shaft, facilitate easy removal and replacement of the triangular diagonal guide.

The preferred procedure for assembling a work-web with its interleaved carbons is to remove all the triangular guides from the carbon-carriage and then replace them seriatim, as one after another of the carbon-sheets is withdrawn from its roll and threaded around a guide. Thus, beginning with the first carbon-sheet for the lowermost plies, the leading edge of said sheet is drawn slightly past the rock-shaft position, the rock-shaft with its attached diagonal guide is then inserted in its bearings, the rock-shaft overlying the sheet, and the sheet is then further pulled forward, turned over said diagonal guide for direction lengthwise of the work-web and carried a suitable distance past said guide. While said sheet is being thus threaded around the guide, the latter may be swung to any convenient position away from the web to facilitate such threading, and the subsequent insertion between corresponding plies of a work-sheet. The next diagonal guide for the next ply is then picked up and inserted into the carriage, the carbon-sheet associated with said guide being then similarly threaded therearound and inserted between its corresponding plies of work-web.

The built-up assembly of rock-shafts thus formed separates and directs the several carbon-sheets, the separation being effected without the necessity of threading the leading ends of the carbon-sheets into the narrow openings of the vertically-spaced rock-shafts.

Other features and advantages will hereinafter appear.

In the accompanying drawings,

Figure 1 is a perspective view, showing the carbon-roll supports and the carbon-turning means.

Figure 2 is a side elevation, looking from the left side of the typewriter, showing the carbon-roll carriage, the arrangement of a work-web therein, and how said work-web extends from

said carriage to and around the typewriter-platen.

Figure 3 is a section taken in a direction crossing the work-web, showing, in elevation, the disposition of the carbon-rolls, the work-web and the carbon-turning guides and carbons interleaved with said work-web, and also showing details of construction of the novel carbon-roll carriage.

Figure 4 is a diagrammatic view, showing how the novel carbon-roll carriage may be used for two separate work-webs, that is, how one work-web may be in use around the platen, while the other work-web is idly retained in said carriage.

Figure 5 is a perspective view, bringing out details of the novel card-turning guide and how it may be inserted and removed from the carbon-roll carriage.

Figure 6 is a perspective, showing details of the novel carbon-roll supports.

Figures 7 and 8 are enlarged views, showing details of means for locking and unlocking the carbon-rolls.

Figure 9 is a diagrammatic view, illustrating how a narrow fan-folded web may be used with the full width of diagonal guides.

Figure 10 is a diagrammatic view, showing how the diagonal guides may be formed to cut the webs at their folds.

Figure 11 is a diagrammatic view, showing how a short diagonal guide may be employed for a narrow web.

Figure 12 is a perspective view, showing details of a carbon-roll and the manner of mounting it on its spindle, the parts being spread out for clear illustration.

Figure 13 is a perspective view, showing a portion of a fan-fold web with some carbons interleaved between some of the plies of said web, and how the other plies may be separated for introducing a carbon after it has been turned by the novel diagonal guides.

The invention is herein illustrated in connection with a fan-fold typewriter of the kind shown in the patent to Wernery & Smith, 1,132,055, dated March 16, 1915, in which a platen-carriage includes a frame 20, Figure 2, guided for letter-feed travel on a front rail (not shown) and a rear rail 21, supported by posts 22 of the typewriter-frame. In said carriage-frame, a platen 23 is mounted on a platen-axle 24, journaled in end plates 25, attached to a cross-shaft 26 for swinging and displacing the platen from its normal writing position shown by the full lines, Figure 2, to the position indicated by the broken lines in said same figure. With the platen in its displaced position, a work-web 27 is more easily introduced to the platen, and the carbons interleaved with the work-web plies are also easily shifted, inasmuch as, in said displaced position, the tortuous course which the web assumes when the platen is in its normal position is straightened out, as fully set forth in said patent.

From a suitable position behind the typewriter, the web may be guided over a cross-member 28 of the novel carbon-carriage, and in a manner and by means to be described, the plies of said web will have been interleaved with carbon-sheets when the web and platen are in writing position.

To facilitate replacement of worn carbon-sheet portions, said sheets are in the form of rolls 30, from which fresh portions may be unwound. Each roll may be made up of a number of superposed sheets, and the rolls may be arranged at the sides of the work-web, the axes of the rolls 150

extending parallel to the path of the work-web, see Figures 1 and 3.

A suitable length of carbon-sheet is led from a roll in a direction crosswise of the work-web, 5 and is turned, over diagonal guides to be described, in the direction of the work-web. The carbon-rolls and carbon-sheet guides are supported in a movable and novel carbon-carriage, so that the interleaved carbons may, by means 10 of said carriage, move as usual with the work-web, as the latter is line-fed, and, furthermore, so that the interleaved carbon-sheets may be retracted to register with a new work-web form after typing on the preceding form has been completed.

For supporting and guiding the carbon-carriage, which, inasmuch as it carries the composite work-web, must also move with the platen-carriage in letter-feed and return directions, 20 there is projected, rearwardly from said platen-carriage, a pair of guide-rails 31. At their rear ends, said rails 31 are spaced and connected by a cross-member 32, to form a frame which, by means of pivoted connections 29, located at the 25 forward ends of said rails 31, is secured to brackets 33 fastened to and extending rearwardly from the platen-carriage frame 20. The typewriter-framework also includes a stationary cross-rail 34 for supporting the guide-rails 31, and along 30 which cross-rail 34 said guide-rails 31 may move as the platen-carriage moves in letter-feed and return directions. For bearing upon said cross-rail, each guide-rail 31 has a roll 35 mounted on a bracket 36 secured to the guide-rail, said bracket including a horizontal tab 37, which, bearing 35 against the under side of the cross-rail 34, prevents upward displacement of the guide-rail.

As it is desirable, on occasion, to replace one carbon-carrier by another, the guide-rails 31 support a truck 38, to which different carbon-carriers may be removably attached. Said truck includes a plate 39 which spans and overlies the two guide-rails 31. Attached by screws 78 to the under side of said plate 39 are grooved rolls 40 which embrace the edges of plates 41, the latter forming rail-flanges and being attached to the tops of the guide-rails 31, by screws 42. The truck-plate 39 thus affords an elongate table-surface upon which different carbon-carriers may be supported. The carbon-carrier of the present invention includes a base 43 formed of sheet-metal, and having its edges turned down, as at 44, to secure stiffness of the base. The base 43 rests upon the truck-plate 39, and, to this end, it may be provided on its under side with elongate bosses 45 extending crosswise of the base 43, as shown in Figure 2. As best seen in Figure 3, said bosses 45 may be pressed out of the sheet-metal forming the base 43. Extending downwardly from said bosses 45, to be received by corresponding openings in the truck-plate 39, are the usual slotted pegs 46, said pegs 46 having slots to receive the edges of holding levers 47, pivoted on studs 77 on the under side of the truck-plate 39, as best seen in Figure 3. The pegs 46 are secured to the base 43, by riveting, washers 48 being interposed between the riveted ends of the pegs and base 43 to thereby hold the pegs securely. It will be evident from said Figure 3 that, with the levers 47 in the position shown, the base 43 of the carbon-carrier is secured to the top of the truck-plate 39. It will also be evident that, if the levers 47 are swung outwardly about said studs 77, that is, away from the pegs 46, the edges of said levers

will be withdrawn from the slots in the pegs 46 and the base 43 and the parts carried thereon to form a carbon-carrier may then be removed. Other carbon-carriers that are to be used with the truck 38 will have similar pegs 46. As shown in Figure 2, the turned-down edges 44 of the base 43 may embrace the front and rear edges of the truck-plate 39.

Retaining brackets 49 for the carbon-rolls and carbon-guides are mounted on the carbon-carrier base 43, and are designed to secure lightness without sacrificing strength. With a fan-folded web, it is necessary to be able to insert carbons from either side of the web; one of the novel brackets 49 is therefore mounted upon the base 43, upon each side of the web. Each bracket 49 may include an elongate base-portion 50, having turned edge-portions 52 to secure stiffness. Said base-portion 50 may also be provided with openings 51 to secure lightness. For attachment to the base 43, the turned edge-portions 52 of said base 50 may be extended to form feet 53, by means of which the bracket 49 may be secured to the base 43 by screws 54. Turned up from the ends of the base-portion 50, and integral therewith, are portions forming supports 55 and 56, in which carbon-roll spindles 57 and rock-shafts 58 may be retained, said rock-shafts 58 forming part of the novel diagonal guides to be described later herein. The length of the bracket-base 50 is such that the spacing of the upturned ends 55, 56 is large enough to include a sufficiently wide carbon-roll 30.

The invention is herein illustrated as embodied in a machine employing four carbon-rolls, 110 two on each side of the work-web; it being understood, however, that the invention is not limited to any specific number of rolls. The carbon-rolls are wound on spools 59. Each spool may have a rectangular opening 60 extending centrally throughout the length of the spool, which opening, as best seen in Figure 12, may at one end of the spool fit over a similar rectangularly shaped hub 61 of a cup-shaped member 62, which may form a retaining flange to abut one end 115 of said spool. The other end of the spool is also provided with a retaining flange 63 having an outer hub 64 and an inner cylindrical hub 65, which latter hub is of a diameter to fit into the opening 60 of the spool. The flange 62 may be 120 keyed to the carbon-roll spindle by a pin 67. The flange 63 is slidable along the spindle 57 to alter the spacing between the flanges, so that different widths of carbon-roll may be accommodated, and said flange 63 may be secured by a 130 set-screw 66 threaded into the outer flange 64 and binding on the spindle 57. An extra flange 112 is for use with narrow spools as will be explained later herein.

The cup-shaped flange 62 has, as best shown 135 in Figures 7 and 8, V-shaped teeth 68 cut in its rim-edge and thereby forming a crown-shaped detent-wheel that co-operates with other parts to lock the spool in a manner to be described. The spindle 57 has each end portion 140 reduced in diameter to form shoulders 69, which may abut the inner sides of the supports 55, 56, and thereby retain the spindle against end-wise displacement. One of the supports, as, for example, 56, may have plain holes 76, Figure 6, 145 each to receive the reduced portion at one end of a spindle 57, the other support 55 being provided with notches 75, each to receive the reduced portion at the other end of said spindle. A latch-plate 70, common to the two spindles 57 that 150

are retained in each of the brackets 49, is mounted on the inner side of support 55, as best shown in Figure 1. As seen in said Figure 1, said plate 70 is elongate and slides endwise on shouldered 5 studs 71, the plate being provided with slots 72 having a slide fit on said studs 71. Said plate 70 also includes hooked portions 73, which embrace the roll-spindle 57 to retain it within the notches 75, when the latch, urged by a spring 74, is 10 in the position shown in Figure 1.

When the latch-plate 70 is moved in the direction of the arrow (Figure 1), the hooked portions 73 thereof will be withdrawn from the spindles 57, and either spindle may then be lifted out. 15 The upper ends of the hooked portions 73 and also the sides of the notches 75 may be formed so that a spindle 57 may be snapped into place by laying the end of said spindle against said upper portion of the hook 73 and notch-side and 20 pressing down the other end of the spindle having first been inserted in its hole 76 in the opposite support 56. Such pressure will cause the spring 74 to yield, and the latch-plate 70 to be displaced, the latch, urged by the spring 74, snapping 25 back into place as the end of the spindle seats itself under said pressure in the notch 75.

As seen in Figure 2, the extent of the truck 38 in the direction of the guide-rails is substantially less than the extent of the carbon-carrier mounted thereon. Said truck 38 would also accommodate a narrower carbon-carrier of the type set forth in the aforesaid Wernery & Smith patent. According to the present invention, the carbon-carrier is extended toward the rear of the machine, to afford sufficient room within which the wide carbon-rolls and carbon-guide may be included. Such rearward extension is substantially beyond the rear side of the truck 38. The rearward extension of the carbon-carrier will therefore overhang the rear ends of the carbon-carriage guide-rails 31 when said truck is pushed back to the ends of said rails 31.

For turning the carbon-sheets from the direction crosswise of the work-web as they are unrolled from the carbon-rolls into a direction along the work-web, there are provided diagonal guides 80, secured to the aforesaid rock-shafts 58 in a manner best seen in Figure 5. As will be seen in said Figure 5, each diagonal guide 80 is one of two portions of an angularly bent wire, the other portion forming a strut 81, to support the free end of the diagonal guide 80. As seen in Figure 5, the other end of the diagonal guide 80 and one end of the strut 81 are inserted in drill-holes 82 of said rock-shaft and firmly held in said holes by any suitable means, as, for example, a forced fit, soldering or riveting. The diagonal guide 80, rock-shaft 58 and strut 81 form a triangular carbon-guide. The rock-shaft 58 is extended sufficiently beyond the diagonal guide 80 and strut 81, so that it may be journaled in the supports 55, 56, which form part of the bracket 49. An object of the invention is to make said triangular carbon-guides easily removable from and replaceable in the supports 55, 56. To this end, one end of each rock-shaft may be chamfered and rounded, as at 84, Figure 5, to facilitate insertion into one of bearing-holes 85 of the support 55. Said bearing-holes 85 may be sufficiently larger in diameter than the diameter of a rock-shaft 58, to permit the rock-shaft to be skewed, so that the other end of said rock-shaft may be passed around the inner surface of the opposite support 56, for insertion into or withdrawal from one of the bearing-holes 86 in sup-

port 56 for said other end of the rock-shaft. Said bearing-holes 86 are formed to include slots 87 through which a flattened head 88 of the rock-shaft may be inserted. Adjacent said flattened head 88 is a cylindrical neck 89, smaller in diameter than the body of the rock-shaft, which is journaled in the cylindrical portion of the hole 86. As seen in Figure 5, it is evident that after insertion of the rock-shaft end, including the flattened head 88 and neck 89, into a hole 86, 87, and, after said rock-shaft has been given a quarter turn, said end of said rock-shaft will be interlocked with the support 56, as indicated at 90. Preparatory to assembling a web interleaved with carbon-sheets, all of the rock-shafts 58 and attached guides 80 are removed from the carbon-carrier and laid aside, ready for use. Sufficient lengths of carbon-sheets are unrolled and allowed to hang idly, as shown, for example, at 91, Figure 13. Said Figure 13 shows a number of plies 92 of the work-web already interleaved with carbon-sheets 93. During such interleavement, the guides 58, 80 were introduced into the carbon-carriage, one after the other. For example, the lower carbon-sheet 93, as shown in Figure 1, will have been picked up first and its leading edge advanced slightly beyond the position to be occupied by the rock-shaft 58. Said rock-shaft 58 will then have been picked up, placed over the carbon-sheet so advanced, and at the same time will have been inserted in its bearings in the supports 55, 56. With the rock-shaft 58 turned so as to elevate the diagonal guide 80 to the position illustrated at 80^a, Figure 13, the leading edge of the carbon-sheet is then advanced further, and said sheet is then turned about said diagonal guide, which is then swung downwardly to bring said guide and the turned sheet to the top of the bottom ply, the plies above being temporarily turned aside as shown in Figure 13. Referring again to Figure 1, and noting that a lowermost carbon-sheet 93 has been threaded around the guide 80 in the manner indicated, said lower sheet coming from a roll at the left of the work-web, it is next in order to introduce the lowermost carbon-sheet coming from the right of the work-web. In the latter case, the leading edge of the carbon-sheet is also advanced to a position just beyond that which the rock-shaft will occupy, said rock-shaft and its attached diagonal guide 80 being then inserted in its supports 55, 56, the carbon-sheet being then advanced and turned about the diagonal guide 80, which, together with the carbon turned thereabout, is then swung downwardly against the next ply of the work-web. If the web is fan-folded, as shown in Figure 13, the carbon-sheets are thus built up alternately from both sides of said web. It will be noticed that after the web is built up, and the rock-shafts 58 with their attached guides 80 are in position, said rock-shafts form vertically-spaced and closely-spaced guides extending crosswise of the carbon-sheets at portions between the carbon-rolls and the edges of the work-web. It has not been necessary to insert the leading edge of every carbon-sheet into the narrow opening between any of the two rock-shafts 58, inasmuch as said rods and their attached guides were assembled seriatim, that is to say, in the case of two adjacent rock-shafts 58, the lower rock-shaft 58 was first in place, then the carbon-sheet laid over it, and on top of that the next rock-shaft 58, and so on, until the assembly was built up.

While the carbon-sheets are being interleaved with the several plies of the work-web, the leading

edge of said web may be slightly in advance of the diagonal guides, that is, in advance of the struts 81 of said guides. Similarly, the leading edges of the carbon-sheets may also extend beyond the 5 struts 81, but preferably not quite as far as the leading edges of said plies. The work-sheet plies and carbons interleaved therebetween are then advanced toward the platen and threaded around said platen while the carbon-carrier is held, the 10 carbon-rolls turning as the interleaved carbon-sheets together with work-web plies are so advanced. It will be understood that during this operation, the platen is in the position shown by the broken lines in Figure 2. The platen is then 15 lowered to its normal writing position, and the carbon-carrier may be retracted far enough to afford a sufficient range of advance for line-feeding. During such retraction, the carbons, if the platen is in its writing position, will be held by 20 said platen, and it is necessary, therefore, that the carbon-rolls be free to revolve. During the regular line-feeding advance of the carbon-carrier, however, the carbon-carrying rolls must be locked, and the parts that cooperate with the 25 previously mentioned detent-member teeth 68 to effect such locking will now be described. For co-operation with said teeth 68 to lock a carbon-roll, there is provided for each carbon-roll a lever 98, pivoted on a bracket 99, which may be secured 30 to the carbon-roll supports 56, by screws 100, said bracket being formed, as indicated in Figures 1, 7 and 8, into an L-shaped piece having two legs, one leg abutting said support 56, and the other leg extending from said support, and carrying the 35 lever 98, which is pivoted on a stud 101, carried by said latter leg. Said latter leg also carries a holding lever 102 for the locking lever 98, said holding lever being pivoted on a stud 103. For manipulation, the locking lever 98 has a finger-piece 104 40 extended to project through an opening 105 of the support 56. Furthermore, said locking lever 98 has an arm having a V-shaped edge 106 which may engage the detent-teeth 68 formed on the flange 62 of the carbon-rolls. Extended beyond 45 and below said edge 106 is a shoulder 107, over which a latching portion 108 of the holding lever 102 may be interposed, as shown in Figure 8, when it is desired to keep the holding lever 98 withdrawn from the detent-flange teeth 68. The 50 locking lever 98 and its holding lever 102 are connected by a spring 109 having points of attachment to said levers, as seen in Figures 7 and 8. It will be seen from Figure 7 that the distance from the axis of said spring 109 to the center of 55 the pivot-stud 101 is such that in conjunction with a suitable strength for said spring, the V-shaped edge 106 of the locking lever 98 is firmly held against the detent-flange teeth 68, and that the corresponding carbon-roll is thereby securely held against rotation. While the locking lever 98 60 is so held in its effective position, the axis of the spring 109 is sufficiently near the center of the pivot-stud 103 of the holding lever 102 to minimize the pressure of said lever 102 upon the locking lever 98. When it is desired to unlock the 65 carbon-roll, the locking lever 98 is, by means of its finger-piece 104, shifted to the position indicated in Figure 8. In this position, the axis of the spring 109 will have increased its distance from the pivot-stud 103 and decreased its distance from 70 the pivot-stud 101, with the result that, whereas the turning power of said spring upon the holding lever 102 is increased, its turning power upon the locking lever 98 is decreased, and said spring, 75 therefore, enables the holding lever 102 to hold

the locking lever 98 in the position indicated in said Figure 8, in which the finger-piece 104 abuts the end of the opening 105. For restoring the locking lever 98 to the detent-teeth 68, a pull upon the finger-piece 104 of said locking lever in the direction of the arrow, Figure 8, overcomes the tension of the spring 109. In this case the locking lever 98 is rotated clockwise and causes the holding lever 102 to be displaced in counterclockwise rotation until its latching portion 108 escapes from the end of the shoulder 107 of the locking lever, whereupon the spring 109 will be effective to force the V-shaped edge 106 of the locking lever into engagement with the detent-teeth 68 again. 80 Some work-webs have plies of different widths as shown in Figure 9. In such case, narrow carbon-sheets 110 are used and are unwound from correspondingly narrow rolls 111. An extra flange 112 may be provided for the narrow roll 111 if it is at the left of the web, it being inexpedient to move the flange 62 to abut the narrow roll 111, because said flange 62 carries the detent-teeth 68, which, in the case where narrow rolls are used, also serve to lock said narrow rolls. Said extra flange 112 has a rectangular hub 113 (see Figure 90 100 12) to fit the opening 60 of the carbon-spool 59, the latter corresponding, of course, in length with the narrow roll. Said flange 112 also has an outer hub 114 in which is threaded a set-screw 115 to bind upon the shaft 57. When a narrow roll is used at the right of the web, the regular flange 63 is simply moved to abut said narrow roll, as shown in Figure 9. Figure 9 shows the use of a fan-fold form with wide folds and narrow folds. The narrow or bottom fold has to be slit 105 110 by guide-rod 80, of the standard carbon-guide in order to pass said rod 80. The wide plies of the fan-fold form pass freely and unslit past the standard carbon-guides. Figure 9 thus shows an arrangement whereby the fan-fold form of wide 115 and narrow plies can be used with standard size carbon-guides, by slitting the narrow folds. 115 It will be seen in Figure 9 that the diagonal guide 80 crosses the folded edge of the narrow web-plies when said guide 80 projects from the same side of the web at which the narrow plies are disposed. It is necessary, therefore, that such folded edge be cut as shown at 116. Such cutting may be done by moving the carbon-carrier 120 backward while holding the whole web, in which case the guide 80 does the cutting, or the cutting may be effected by a separate operation in any suitable manner, as, for example, by running a knife down said folded edge. In some cases, however, where a web having plies of different widths is used, it is desirable to retain the plies in their fan-folded form after a form has been typed on and detached from the web. Figure 11 shows an arrangement whereby a fan-fold web of 125 wide and narrow folds is used without slitting 130 any of the folds. For this purpose a carbon-guide having a short diagonal reach may be used for the narrow fold, which freely passes the short-reach carbon-guide without being slit. The short-diagonal reach carbon-guide is arranged to be mountable in the same supports as 135 mount the standard carbon-guides so as to be interchangeable with the latter. By mounting the diagonal guides 80 on the rock-shafts 58, said guides may be made of different lengths, for 140 a web having fan-folded plies of different widths, the folds of which plies are not to be cut. As seen in Figure 11, a short diagonal guide 117 is fastened to a regular rock-shaft 58 in the same manner already described for fastening the 145 150

longer guide 80, such short diagonal guide 117 being employed wherever a carbon is to be interleaved from the side of the web at which the narrow web-plies are to be disposed, that is to say, if the interleavement from such side of the web is to be between narrow plies, a short guide 117 is used. If the interleavement is to be between full-width plies, a guide 80 of full length may be used. In any case, if the interleavement 10 is from the other side of the web, guides 80 of full length may be used irrespective of whether such interleavement is between wide or narrow web-plies. The use of the short diagonal guides 117 also avoids the necessity for providing the 15 extra flange 112 for the carbon-rolls at the left of the web, the regular flanges 63 being suitable, as will be evident from Figure 11.

Figure 10 illustrates how a diagonal guide may 20 be extended beyond the folds of a fan-folded web to cut said folds, as indicated at 118. To afford such extension 119 of the diagonal guide 80 without a corresponding increase of the length 25 of the rock-shaft 58, on which such extended guide 80 is mounted, the wire forming said guide may have a reverse bend at a point 120, which lies beyond the fan-folded edge. From said point 120 the wire may extend in a direct line to its point of attachment 121 with the rock-shaft 58, or, as is preferable and illustrated, the 30 wire may be bent and directed from said point 120 to include a bend 122, from which the wire extends perpendicularly to the rock-shaft 58 to its point of attachment 121.

The wire forming the diagonal guide 80 may 35 also have a bend 123 just outside the edge of the carbon-sheet, the purpose of this bend being to incline the cutting portion or extension 119 of the diagonal guide more toward the folded edge of the web, and thereby facilitate the cutting 40 of said edge.

For guiding the work-web laterally, there may 45 be provided the usual guides 124, which are adjusted laterally of the work-web along the cross-member 28, which may be secured in brackets 126 extending from the rear end portions of the carbon-roll brackets 49, said brackets 126 being secured to the under side of said carbon-roll brackets by screws 127. Where a narrow carbon-bracket is mounted on the truck 38, the cross-member 50 may be retained in upstanding brackets 128 projecting from the rear portions of the carbon-rail frame along which the carbon-carriage moves, said brackets being usually attached to the ends of the cross-member 32 of said frame. 55 It will be noticed that the feet 53 of the carbon-spool brackets 49 are high enough to elevate the base-portion 50 of said brackets 49 above said upstanding brackets 128, thus enabling said base-portion 50 to clear said brackets 128 or any rod 60 that may span said brackets 128.

The platen-carriage includes the usual paper-table 129, a front paper-table 130 and a tie-rod 131 connecting end plates 132 of said carriage. Said tie-rod 131 also serves as an abutment for 65 the end plates 25 of the swingable platen-frame. The usual gage 125 for positioning the leading edge of the work-web, preparatory to detaching a finished form from said work-web, is fastened to the front paper-table. For moving the carbon-carriage back and forth conveniently from a 70 position in front of the typewriter, there is provided an arm 135 formed as best seen in Figures 1 and 2. For attachment to the right carbon-roll bracket 49, said arm may have an ear 136 abutting the upstanding carbon-roll support 56 of

said bracket and may also have a rearward extension 137 which abuts the under side of the base-portion 50 of said bracket, as best seen in Figure 2. With the ear 136 and extension 137 thus abutting said bracket, said arm 135 may be held in place by screws 138.

For supporting the work-web against sagging at the portion where the diagonal guides bear on the several plies of said web, there may be provided a flat piece 133 which underlies the strut-portions 81 of said diagonal guides.

Said flat piece 133 forms part of a bracket 134, which is extended upwardly from the base 43 of the carbon-carrier, so that said flat piece may support said web. The bottom ply of the web is in immediate contact with said flat piece 133, as seen in Figure 3, and the strut-portion 81, immediately above said bottom ply and resting thereon, cooperates with said flat piece 133 to support the web against sagging.

Figure 4 shows how two separate work-webs may be accommodated at one time by the carbon-carrier, one of said webs being in use and the other one being idle. The leading end of the idle web may be tucked between two struts 81 of two 100 diagonal guides, said two guides being inserted in the carbon-carrier in addition to the guides that are between the plies of the two separate webs.

Variations may be resorted to within the scope 105 of the invention, and portions of the improvements may be used without others.

Having thus described my invention, I claim:

1. The combination with a typewriting machine having a platen, of means for guiding a multiple-ply work-sheet web to said platen, a carbon-carrier movable on said machine toward and away from said platen, said carbon-carrier including means for holding superposed carbon-sheets to be directed crosswise of said web and then turned 110 in the direction of said web, means for separating said carbon-sheets and effecting the turning thereof, said separating and turning means including a plurality of vertically-spaced rods for separating and guiding the carbon-sheets as they 120 are directed crosswise as aforesaid, each rod having a carbon-turning member fastened thereto and positioned to extend diagonally across the work-web, and means mounting said rods for rotation, so that the carbon-turning members may 125 be swung toward and from the work-web.

2. The combination with a typewriting machine having a platen, of means for guiding a multiple-ply work-sheet web to said platen, a carbon-carrier movable on said machine toward and away 130 from said platen, said carbon-carrier including means for holding superposed carbon-sheets to be directed crosswise of said web and then turned in the direction of said web, means for separating said carbon-sheets and effecting the turning thereof, said separating and turning means including a plurality of vertically-spaced rods for separating and guiding the carbon-sheets as they 140 are directed crosswise as aforesaid, each rod having a carbon-turning member fastened thereto and positioned to extend diagonally across the work-web, and means mounting said rods for rotation, so that the carbon-turning members may be swung toward and from the work-web, said rods and mounting means being arranged so that 145 the rods and their attached carbon-turning members may be readily removed from and replaced in the carbon-carrier.

3. In a type-impressing machine having a platen over which a work-web travels, the combina- 150

tion with carbon-spools mounted at opposite sides of the path of travel of the incoming work-web, of a plurality of vertically-spaced rods for separating and guiding the transversely incoming carbons, each rod having a carbon-turning member fastened thereto and positioned to extend diagonally across the work-web to alter the course of the transversely incoming carbons into correspondence with the direction of travel of the incoming work-web, and means mounting said rods for rotation, so that the carbon-turning members may be swung toward and from the work-web.

4. In a type-impressing machine having a platen over which a work-web travels, the combination with carbon-spools mounted at opposite sides of the path of travel of the incoming work-web, of a plurality of vertically-spaced rods for separating and guiding the transversely incoming carbons, each rod having a carbon-turning member fastened thereto and positioned to extend diagonally across the work-web to alter the course of the transversely incoming carbons into correspondence with the direction of travel of the incoming work-web, and means mounting said rods for rotation, so that the carbon-turning members may be swung toward and from the work-web, said rods and mounting means being arranged so that the rods and their attached carbon-turning members may be readily removed from and replaced in said mounting means.

5. In a type-impressing machine having a platen over which a work-web travels, the combination with carbon-spools mounted at opposite sides of the path of travel of the incoming work-web, of a plurality of vertically-spaced rods for separating and guiding the transversely incoming carbons, each rod having a carbon-turning member fastened thereto and positioned to extend diagonally across the work-web to alter the course of the transversely incoming carbons into correspondence with the direction of travel of the incoming work-web, and means mounting said rods for rotation, so that the carbon-turning members may be swung toward and from the work-web, said rods and mounting means being arranged so that the rods and their attached carbon-turning members may be readily removed from said mounting means, and replaced seriatim in said mounting means one after another, between the plies of the work-web in building up the composite web.

6. A type-impressing machine including a platen over which travels a work-web folded lengthwise to form folds of different widths, carbon-sheets of different widths being projected transversely to the web from the opposite sides of the latter, carbon-turning flaps, and supports on each side of the web-path in which said flaps are pivoted, the supports on each side being spaced sufficiently apart to clear the widest carbon-sheet and mount its turning flap, each flap having a reach extending diagonally of the web for turning the transversely-incoming carbon-sheet in the direction of web-travel, the pivot-axes of the flaps being arranged on opposite sides and lengthwise of the web, so that the flaps may be swung to idle positions off from the web, some of said flaps having diagonal reaches of greater dimensions than the reaches of other flaps to correspond with the differences in the widths of web-folds, and thereby avoid severing the narrow folds, the carbon-turning flap used with the relatively narrow folds being arranged to have a support-bridging span substantially exceeding the compass of its relatively short diagonal reach and being

thereby pivotally mountable in said supports interchangeably with a carbon-turning flap for the wider web-folds.

7. A type-impressing machine including a platen over which a work-web, fan-folded lengthwise, travels, means from which a pair of carbon-sheets are projected transversely of the web from opposite sides of the latter, a carbon-turning flap pivoted beyond one side of the web path, and another flap pivoted beyond the opposite side of the web path, each flap having a reach extending diagonally of the web for altering the course of the transversely incoming carbon-sheet to the direction of travel of the web, the pivot-axes of the flaps being arranged on opposite sides and lengthwise of the web so that the flaps may be swung to idle positions, off from the work-web, or returned to working positions, said flaps being constructed so that the ends of the diagonal reaches are at different distances from their respective pivot-axes so as to fall within the folded edges of web-plies traveling over said platen in asymmetrical, laterally spaced relation to said pivot-axes, each flap having a rod forming the pivot-axe and also forming a primary guide for the transversely incoming carbon-sheet.

8. A type-impressing machine including a platen over which a work-web, fan-folded lengthwise, travels, means from which a pair of carbon-sheets are projected transversely of the web from opposite sides of the latter, a carbon-turning flap pivoted beyond one side of the web path, another flap pivoted beyond the opposite side of the web path, each flap having a reach extending diagonally of the web for altering the course of the transversely incoming carbon-sheet to the direction of travel of the web, the pivot-axes of the flaps being arranged on opposite sides and lengthwise of the web so that the flaps may be swung to idle positions, off from the work-web, or returned to working positions, said flaps being constructed so that the ends of the diagonal reaches are at different distances from their respective pivot-axes so as to fall within the folded edges of web-plies traveling over said platen in asymmetrical, laterally spaced relation to said pivot-axes, each flap having a rod forming the pivot-axe and also forming a primary guide for the transversely incoming carbon-sheet, and means pivotally supporting the flaps at the ends of the rods, said rod-ends and supporting means being arranged so that the flaps may be readily removed and replaced.

9. The combination with a typewriting machine having a platen, of means for guiding a fan-folded multiple-ply work-web to said platen, the plies of said web being of different widths, a carbon-carrier movable on said machine toward and away from said platen, said carbon-carrier including means for holding superposed carbon-sheets to be directed crosswise of said web, and then turned in the direction of said web, said carbon-sheets being of different widths corresponding to the different widths of the web-plies, means for separating said carbon-sheets and turning them in the direction of the work-web, said separating and turning means including a plurality of vertically-spaced rods, separating and guiding the carbon-sheets as they are directed crosswise as aforesaid, each rod having a carbon-turning member fastened thereto and positioned to extend diagonally across the work-web, the lengths of said turning members being different in accordance with the different widths of the work-web plies, and means mounting said rods

for rotation, so that the carbon-turning members may be swung toward and from the work-web.

10. The combination with a typewriting machine having a platen, of means for guiding a fan-folded multiple-ply work-web to said platen, the plies of said web being of different widths, a carbon-carrier movable on said machine toward and away from said platen, said carbon-carrier including means for holding superposed carbon-sheets to be directed crosswise of said web, and then turned in the direction of said web, said carbon-sheets being of different widths corresponding to the different widths of the web-plies, means for separating said carbon-sheets and turning them in the direction of the work-web, said separating and turning means including a plurality of vertically-spaced rods, separating and guiding the carbon-sheets as they are directed crosswise as aforesaid, each rod having a carbon-turning member fastened thereto and positioned to extend diagonally across the work-web, the lengths of said turning members being different in accordance with the different widths of the work-web plies, and means mounting said rods for rotation, so that the carbon-turning members may be swung toward and from the work-web, said rods and mounting means being arranged so that the rods and their attached carbon-turning members may be readily removed and replaced in the carbon-carrier.

11. In a type-impressing machine having a platen over which a work-web travels, the combination with carbon-spools mounted at opposite sides of the path of travel of the incoming work-web, of a plurality of vertically-spaced rods for separating and guiding the transversely incoming carbons, each rod having a carbon-turning member fastened thereto and positioned to extend diagonally across the work-web to alter the course of the transversely incoming carbons into correspondence with the direction of travel of the incoming work-web, and means mounting said rods for rotation, so that the carbon-turning members may be swung toward and from the work-web, said mounting means including a pair of spaced-apart plates, in which said rods are journaled, one end of each rod being formed with a head having flattened sides and an adjacent cylindrical neck of less diameter than said rod and slightly longer than the thickness of one of said plates, the corresponding plate in which said rod-end is inserted having cylindrical holes and notches extending from the sides of said holes, said notches receiving said flattened head and the cylindrical portion of the hole receiving said neck, the flattened head projecting beyond the plate when said neck is thus received, and a turn of the rod sufficing to interlock said rod with said plate by means of said head and neck.

12. In a typewriting machine having a platen and a platen-carriage movable in letter-feed and return directions, manifolding means for typing a multiple-ply work-web, said means including spools from which carbon-sheets are directed transversely of said web and then turned in the direction of said web, carbon-guides for so turning the carbon-sheets, a carbon-shifting carriage supporting said spools and carbon-sheet guides, and guide-rails extending rearwardly from the platen-carriage, said carbon-shifting carriage including a truck movable on said rails, and spaced supports on the truck for the spools and carbon-guides, said truck, supports, and guide-rails being arranged so that the transverse

carbon-stretches substantially overhang the rear ends of the rails when the carbon-shifting carriage is in its rearmost position, the front edge of said transverse carbon-stretches being thereby correspondingly spaced from the platen-carriage, and the length of said rails being thereby minimized for a given range of carbon-shifting movement.

13. In a typewriting machine having a platen-carriage for carrying a multiple-ply work-web, the combination with elongate carbon-spools and elongate carbon-directing guides, of a carbon-carriage, and guide-rails extending rearwardly from the platen-carriage on which said carbon-carriage moves rearwardly and forwardly, said carbon-carriage including an elongate truck bearing on said guide-rails and extending in its long dimension transversely of the web path to include end portions beyond the sides of said path, and elongate supports mounted on said end portions of said truck for holding the elongate spools and carbon-guides at the sides of said path, said elongate supports extending in their long dimension transversely of the long dimension of said truck and substantially beyond the rear end of said truck, the forward ends of said elongate supports being substantially even with the forward end of said truck, the transverse carbon-stretches incoming from the carbon-spools thereby substantially overhanging the rear ends of the rails when the carbon-carriage is in its rearmost position, the front edges of said carbon-stretches being correspondingly spaced from the platen-carriage, and the length of said rails being thereby minimized for a given range of carbon-shifting movement.

14. The combination with a typewriting machine having a platen, of manifolding means including a carbon-spool mounted for rotation to unroll carbon-sheets therefrom, and locking means for holding said spool against rotation, said locking means including a toothed detent-member keyed to said spool, a pivoted locking lever operable to engage the tooth-member or to be disengaged therefrom, a second pivoted lever to hold the locking lever in its disengaged position, and a spring common to both levers, said spring having one end attached to one lever, and the other end attached to the other lever, said spring, levers and the lever-pivots being arranged so that when the locking lever is engaged, it is urged by said spring against said detent-member, and, furthermore, so that when said locking lever is disengaged, the second lever, urged by said spring, yieldably holds the locking lever in its disengaged position, said locking lever having a finger-piece whereby it may be moved to its locking or disengaged position.

15. In a manifolding type-impressing machine having a platen over which a multiple-ply web travels; a carbon-carrier movable on said machine toward and away from said platen for carrying a pair of carbon-spools, each having at one end a trunnion, a support on said carrier having end members in which said spools may be journaled, one end member having spaced U-shaped seats for the spool-trunnions, the other member having spaced pivotal bearings, for the other ends of the spools, arranged for removal from or placement of a spool in said support by endwise and tilting movement of the latter, and a single spring-pressed retractable slide having spaced fingers, said slide and fingers being arranged to engage and releasably lock the trunnion-ends of the spools in said U-shaped seats,

said fingers arranged so that by pressing the trunnion-end of a spool thereagainst for placement of a spool in the support, the slide is momentarily displaced and the trunnion thereby snapped into said U-shaped seat.

16. In a type-impressing machine having a platen over which a fan-folded web travels, the combination with carbon-spools mounted at opposite sides of the path of travel of the incoming work-web, of a plurality of vertically-spaced rods for separating and guiding the transversely incoming carbons, each rod having a carbon-turning member fastened thereto and positioned to extend diagonally across the work-web to alter the course of the transversely incoming carbons into correspondence with the direction of travel of the incoming work-web, and a carriage on which said spools and also the rods having the attached carbon-turning members are mounted for movement with the work-web in line-feeding direction and in a reverse direction for retracting the carbons while the web is held, said carbon-turning members extending beyond the edges of said web, so that they cut the folds thereof during the carbon-retracting movement of said carriage.

17. In a type-impressing machine having a platen over which a work-web travels, the combination with carbon-spools mounted at opposite sides of the path of travel of the incoming work-web, of a plurality of vertically-spaced rods for separating the transversely incoming carbons, each rod having an angularly bent wire fastened thereto, so that one portion or leg of said wire extends from said rod diagonally across the work-web to alter the course of the transversely incoming carbons into correspondence with the direction of the incoming work-web, the other portion or leg forming a strut between the otherwise free end of said diagonal portion and said rod, and means mounting said rods for rotation, so that the angularly bent wire may be swung toward and from the work-web.

18. In a type-impressing machine having a multiple-ply work-web carriage including a platen; a carbon-carrier mounted on guide-rails extending rearwardly from said carriage for movement to and from said platen and carrying elongate carbon-spools on opposite sides of the web path and also carrying carbon-guides for directing the transversely incoming carbons and turning them in the direction of the work-web, said carrier including a truck having an elongate platform extending in its long dimension crosswise of the work-web, and a spool and carbon-guide support, said support including an elongate base-plate resting upon and removably attached to said platform, and brackets for supporting said spools and guides, said brackets being each formed of one-piece sheet-metal to include an elongate base-portion turned down on its long edges to secure stiffness, the turned-down edges being bent laterally to form feet, the base-portion of each bracket having formed integrally therewith upturned ends between and by which said spools and carbon-guides are supported, said feet of said brackets being arranged and secured to said base-plate so that each bracket is substantially offset rearwardly of the base-plate and hence of the truck-platform, said carbon-spools thereby substantially overhanging the rear end of said truck-guide-rails when the truck is in its rearmost position.

19. A carbon-directing flap for use in a multiple-ply web type-impressing machine using car-

bons incoming transversely from the side of the web, said machine having spaced supports in which said flap is to be removably and pivotally mounted, said flap including a rod for spanning said supports and arranged at its ends for detachable pivotal connection to said supports, and a reach secured to and extending at an angle from said rod to cross the web diagonally, said rod capable of serving as a guide for the transversely incoming carbon, and said reach serving to alter the course of the transversely incoming carbon into correspondence with the direction of travel of the web.

20. A multiple-ply web type-impressing machine having a plate-carriage, and also having, in combination with a carbon-carrier shiftable to and from said carriage, means on said carrier for mounting a carbon-roll wound on a core, said core having at one end a key-formation, said means including spaced supports fixed on said carrier, an axle journaled in said supports, a toothed flange fastened to said axle, said flange having means to fit said key-formation and to hold the corresponding end of the core centered on said axle, a second flange on said axle arranged to abut and hold the other end of said core centered on the axle and also arranged for removal from and for adjustment along said axle for replacement of a carbon-roll and for different lengths of carbon-rolls, and a detent on said carrier engaging the toothed flange, said supports and axle being arranged for quick removal or replacement of the axle together with the parts mounted thereon.

21. In a carbon-carrier movable along a feedable work-web and having means beyond the side of the web from which a carbon-sheet is projected transversely of the web, the combination of a rod for guiding the transversely incoming carbon-sheet, said rod having a carbon-turning member fastened thereto, said member extending diagonally across the web to alter the course of the transversely incoming carbon-sheet to a course lengthwise of the web, and a pair of spaced supports mounting said rod for rotation so that the carbon-turning member may be swung toward and from the web, one end of the rod being formed with a head having flattened sides and an adjacent cylindrical neck of less diameter than the rod and slightly longer than the thickness of the support in which said rod-end is received, said receiving support having a cylindrical hole and notches extending from the sides of the hole, the notches admitting said flattened head and the cylindrical portion of the hole receiving said neck, the flattened head projecting beyond the support when said neck is thus received, a turn of the rod causing said rod to interlock with said support by means of said head and neck, the other support being arranged to detachably pivot the other end of the rod.

22. In a type-impressing machine having a platen over which a work-web travels; a carbon-carrier including carbon-supply means at the side of the web from which a plurality of carbon-sheets are projected in superposed relation transversely of the web, a plurality of vertically spaced rods for separating and guiding the transversely incoming carbons, each rod having a carbon-turning member fastened thereto, said member extending diagonally across the web to alter the course of the transversely incoming carbon into correspondence with the direction of travel of the incoming work-web, and means mounting said rods for rotation so that the carbon-turning

members may be swung toward and from the web.

23. In a type-impressing machine having a platen over which a work-web travels; a carbon-carrier including carbon-supply means at the 5 side of the web from which a plurality of carbon-sheets are projected in superposed relation transversely of the web, a plurality of vertically spaced rods for separating and guiding the transversely 10 rods for separating and guiding the transversely incoming carbons, each rod having a carbon-turning member fastened thereto, said member extending diagonally across the web to alter the course of the transversely incoming carbon into correspondence with the direction of travel of the incoming work-web, and means mounting 15 said rods for rotation so that the carbon-turning members may be swung toward and from the web, said rods and mounting means being arranged so that the rods and their attached carbon-turning members may be readily removed 20 from and replaced in said mounting means.

24. The carbon-carriage arranged as set forth in claim 13, said carriage including a member extending transversely of the web and spaced rearwardly of the elongate carbon-spool supports 25 to support the trailing portion of the incoming web against sagging upon the carbons.

25. A type-impressing machine including a platen over which travels a work-web folded lengthwise to form folds of different widths, carbon-sheets of different widths being projected transversely to the web from the opposite 30 sides of the latter, carbon-turning guides, and carbon-guide supports on each side of the web-path, the supports on each side being spaced sufficiently apart lengthwise of the web-path to clear the widest carbon-sheet and mount its 35 turning guide, each guide having a reach extending diagonally of the web for turning the transversely-incoming carbon-sheet in the direction of web-travel, the diagonal reaches of the guides being of different dimensions to correspond with the differences in the widths of the web-folds, and thereby avoid severing the narrow folds, the carbon-turning guide used with the relatively narrow folds being arranged to have a support-bridging span substantially exceeding the compass of its relatively short diagonal reach and being thereby mountable in the supports interchangeably with a carbon-turning guide for the 40 wider web-folds.
